UNITED STATES PATENT OFFICE.

JOHN A. BERGREN, OF LAKE PARK, MINNESOTA, ASSIGNOR TO CARL E. YOUNGBERG,
OF SEATTLE, WASHINGTON.

LEVER.

Application filed October 23, 1920. Serial No. 418,973.

To all whom it may concern:

Be it known that I, JOHN A. BERGREN, a citizen of the United States, residing at Lake Park, in the county of Becker, State 5 of Minnesota, have invented a new and useful Improvement in Levers, of which the following is a specification.

This invention relates to operating levers which are to be locked against the load as 10 to movement in one or both directions, such as, for example, levers for operating reversing mechanisms, steam-throttle levers, and the object is to provide a lever which is unlocked by its initial movement in the desired direction.

In the accompanying drawing illustrating the preferred and complete embodiment of the invention:

Figure 1 is a front elevation of the 20 lever;

Fig. 2 is a side elevation thereof, indicating the support in section;

Fig. 3 is an enlarged vertical section on the line 3—3 of Fig. 2, with parts in the 25 plane of section shown in elevation;

Figs. 4 and 5 are front and side elevations, respectively, of one of the locking dogs or plungers; and

Figs. 6 and 7 are a bottom plan and elevation, respectively, of one of the guide nuts.

The operating arm 1, provided with handle 2, and the load arm 3, having an eye 4 for attachment of the load connection 5, are fulcrumed upon a stud 6, the arms having 35 hubs 7, 8 for the purpose. Said hubs are formed, respectively, with interfitting jaws 9, 9 and 10, 10, which jaws are seen in Fig. 3 to have spaces 11 between them, permitting slight initial movement of the operating or power arm in either direction before it urges the load arm.

A pair of lock segments 12, constituting a fixed locking part, are supported, face to face, by pins 13, projecting from the base. 45 Each segment has teeth 14 formed to lock in respect to movement in one direction while permitting latching in the opposite direction; the teeth of the two segments being reversed.

50 The cooperating locking part comprises a pair of plungers 15 passing, in laterally offset planes, through spring chambers 16 in a block portion 17 of the load arm, which juts beneath the segments. The working end 18

of each plunger or dog projects from a guide opening 19 in one end of its spring-chamber into engagement with the teeth of the corresponding segment, and is inclined upon one side and abrupt upon the other. The other end of the plunger is guided in the axial aperture 20 of a nut 21, having a threaded stem 22 which is screwed into this end of the chamber. The projecting head of each of these nuts is slotted, as indicated at 23, and these slots receive laterally projecting toes 24 on the lower or rear ends of the plungers. Said toes are preferably sloped, as shown at 25, upon their outer or remote sides. The plungers are yieldingly pressed into engagement with the segments by 70 springs 26 in the spring chambers, confined between the nuts 21 and collars 27 on the plungers.

The operating arm 1 has an extension 28 passing in front of the portion 17 of the load arm, and terminating in a duplex or bifurcated cam 29, having reversely inclined cam surfaces 30, constituting tripping means arranged to act, respectively, upon the inclines 25 of the toes 24, to displace the respective dogs from locking engagement with the segments or segment.

It will thus be seen that movement of the operating arm in either direction desired will not apply the power at once to the load arm, and that this initial free movement will cause the corresponding cam surface 30 to act upon the toe of the appropriate plunger dog 15, retracting the latter, and holding it out of engagement with its segment, so that the lever can be moved onward in the same direction as the initial movement, to any distance desired. In this operation the other dog latches or rides idly, but is always ready to lock against reverse movement. When 85

the handle is released the spring of the retracted plunger restores it to engagement with its segment, and by pressure of the toe upon the cam also restores the jaws 9, 9 of the operating arm to mid-position with respect to the jaws 10, 10 of the load arm. Desired movement in the opposite direction is effected in the same manner, the other dog and camming surface then coming into play.

100 It will be understood that numerous changes may be made. While the invention has been shown applied to a lever of the first

order, it is not limited thereto. Also, a single acting lever may be had by omitting one of the segments and dogs.

What is claimed as new is:

- 5 1. A self-unlocking lever, comprising an operating arm, a load arm fulcrumed coaxially therewith, said arms having a lost-motion connection whereby the operating arm has initial free movement and thereafter urges the load arm, means including a longitudinally movable plunger for locking the load arm, and means on the operating arm whereby the initial movement thereof in the desired direction moves said plunger and unlocks the load arm to permit movement thereof by continued movement of the operating arm.
- 10 2. A self-unlocking lever, comprising an operating arm, a load arm, said arms having concentric shouldered hubs forming a lost-motion connection whereby the operating arm has initial free movement and thereafter urges the load arm, means for locking the load arm comprising a fixed part and a movable part connected to the load-arm, and a member connected to the operating arm which by initial movement of said arm in the desired direction displaces said movable part from locking engagement with the fixed part.
- 15 3. A self-unlocking lever, comprising an operating arm, a load arm, said arms having a lost-motion connection whereby the operating arm has initial free movement and thereafter urges the load arm, a locking segment, a longitudinally movable locking plunger connected to the load arm, and a cam connected to the operating arm for retracting said dog through the initial movement of the operating arm in the desired direction.
- 20 4. A self-unlocking lever, comprising an operating arm, a load arm, said arms having a lost-motion connection whereby the operating arm has initial free movement and thereafter urges the load arm, a locking segment, a cooperating spring-pressed plunger connected to the load arm provided with a toe, and a cam connected to the operating arm cooperative with said toe to retract the plunger through the initial movement of the operating arm in the desired direction.
- 25 5. A self-unlocking lever, comprising an operating arm, a load arm, said arms having a lost-motion connection whereby the operating arm has initial free movement and thereafter urges the load arm, a spring chamber connected to the load arm, a locking segment, a spring-pressed locking plunger passing through the spring chamber and having a laterally projecting toe, a slotted guide in one end of said spring

chamber confining said toe against turning, and a cam connected to the operating arm to act upon said toe through initial movement of the operating arm in the desired direction.

6. A self-unlocking lever, comprising an operating arm, a load arm, said arms having a lost-motion connection whereby the operating arm has initial free movement and thereafter urges the load arm, two reversely toothed locking segments, the teeth of each being adapted for locking in one direction and latching in the opposite direction, two dogs connected to the load arm cooperating with the respective segments, and a duplex cam connected to the operating arm cooperating with the dogs, substantially as set forth.

7. In a device of the class described, a lever, a member movable by said lever and having a lost motion connection therewith, means for normally holding said member against movement in either direction, comprising a pair of segments having reversely arranged teeth, and means for releasing the member for movement in either direction by initial movement of the lever in such direction.

8. A device of the class described having in combination, a lever and load member concentrically pivoted and having engaging hooks with a lost motion connecting means formed thereon, a fixed locking member at one side of said pivot, said load member extending beyond said locking member and carrying locking means co-operating with said member and said lever having an extension projecting beyond said load member, having means thereon for co-operating with said locking means to release the same upon swinging movement of said lever in either direction whereby movement of said load member with said lever is permitted.

9. A device of the class described having in combination, a lever having an intermediate hub, a pivot member upon which said hub is mounted, a load carrying member having a hub mounted on said pivot and extending at one side thereof substantially parallel with one end of said lever, said hubs being in contact and having recesses in their adjacent surfaces forming a lost motion connection therebetween, an arcuate holding member between said lever and load member, a plurality of means carried by said load member engaging said holding member to lock the load member in position, and means carried by said lever engaging said last mentioned means to unlock said load member upon initial movement of said lever.

JOHN A. BERGREN.
